UNITED STATES PATENT OFFICE.

CHARLES NESSLER, OF NEW YORK, N. Y.

DEVICE FOR WAVING NATURAL HAIR.

Application filed October 5, 1921. Serial No. 505,451.

To all whom it may concern:

Be it known that I, CHARLES NESSLER, a citizen of the United States, and resident of New York city, in the county of New York and State of New York, have invented certain new and useful Improvements in Devices for Waving Natural Hair, of which the following is a specification.

In the art of permanent waving of the hair on the human head as now practiced, the tress or strand of hair after being wound in helical form around a rod and secured thereto by a cord or otherwise, is surrounded or covered in any one of several different ways with a suitable absorbent material which is wetted and is in some way provided with or conveniently carries a hair-treating substance, such for example as borax powder, which of course is also wetted, and an enclosing or housing tube, which is preferably made of non-absorbent material, surrounds the absorbent material carrying said hair-treating substance, the assembled parts being then inserted in a suitable heater so that the heat may act upon the moisture and produce the permanent wave in the twisted hair. My present invention relates to the absorbent means or carrier of the hair-treating substance and has in view several objects, including the provision of means for carrying or containing the hair-treating substance in a uniformly distributed disposition of the same and in a manner that will serve to maintain such distribution during the handling and use of the appliance so that the substance will not shift and get out of place; also a peculiar construction and arrangement of the parts whereby the manufacture of the appliance is quickened and the cost accordingly reduced.

The invention also provides a novel arrangement for grouping or stacking the appliances or absorbent carriers in a neat and handy manner for rapid handling of the same in performing the hair waving process in which it is usual to use a considerable number of the articles in quick succession and at a time when it is desirable to expedite the operation and to avoid a mess as much as possible. With these and other objects in view my invention consists in the various novel and peculiar constructions and arrangements of the several different parts, all

as hereinafter fully set forth and then pointed out in the claims.

I have illustrated types of my invention in the accompanying drawings, wherein,

Fig. 1, is a perspective view of a holder for a number of the absorbent appliances with a door at the lower front edge of the same shown as swung open ready for the withdrawal by hand of the bottom one of the stack of articles contained in the holder.

Fig. 2, is a vertical section of the holder shown in Fig. 1, with the door thereof closed.

Fig. 3, is a perspective view of my improved absorbent appliance.

Fig. 4, is a plan view of the same opened out so as to show the interior structure.

Fig. 5, is a cross sectional view of the article shown in Fig. 3.

Fig. 6, is a cross sectional view of a modified form of the absorbent article.

Referring to the drawings in which like numerals of reference designate like parts throughout, 1 is a box or container having removable top 2, which fits preferably air tight when in place and through which access is had to the interior of the container for inserting therein a stack of the absorbent appliances 3. The front wall of the container is cut away at 4, at the lower edge sufficiently to permit the easy withdrawal in a horizontal direction of the bottom, one of the absorbent articles, a finger notch 5, being formed in said cut away edge to aid the operator in grasping the edge of the bottom article in the act of sliding it out for removal when it is to be used. The forward edge of the bottom of the container is cut away at 6, to give better access to the front edge of the bottom article in grasping it for withdrawal, and these openings afforded by said cut away portions 4 and 6, are closed by a snugly fitting swinging door 7, which is L-shaped in cross section and is hinged on the bottom of the container at 8. A finger piece or grasp 10, is arranged upon the edge of the door for readily opening it. A spring 9, acts upon the door and maintains it normally closed so that the container 1, is practically air tight and moisture retaining and thereby serves to keep the stack of absorbent articles 3, in the desirable wet condition after they are wetted with a lotion, such as

water, and placed in the container. The container thus serves as a constant source of supply of the wet absorbent articles and may be replenished with new ones as they are 5 diminished in using them.

My improved article 3, comprises recessed, or perforated material 11, adapted to carry and practically retain in its recesses or cavities a hair-treating substance 10 12, such for example as borax powder, and a layer of absorbent material 13, covering the recessed material or core 11, so as to be interposed between the latter and the twisted strand of hair when the appliance is 15 placed therearound. The absorbent covering 13, preferably covers both sides of the recessed material 11. This form of the article may be made by first cutting to size a piece of suitably recessed, fitted or perforated material, such for example as ordinary open-work fabric or cotton netting 20 having suitable sized recesses or openings 14 therein for receiving and retaining a hair-treating substance, such as borax powder, then placing this upon a sheet of absorbent material 13, made for example of ordinary cotton cloth, or absorbent paper or fibrous material, of slightly more than double the size of the piece 11, as shown 25 in Fig. 4, and then placing the hair-treating substance, such as dry borax upon the material 11 and substantially filling the openings or recesses 14 thereof, and then turning over the edges of the covering material 13, so that three of the edges of the borax filled piece 11, are bound thereby, after which operation the remaining free portion of the covering material 13, is folded evenly over upon the piece 11, thereby forming 30 a complete cover enclosing the part 11, containing the packed hair-treating powder 12, as shown particularly in Figs. 3 and 5. This completes the construction of the article and it is now in condition for use, or 35 for storage for future use and it is found that in handling the article thus made, practically none of the hair-treating powder will escape and particularly after the article has been wetted, for in wet condition 40 the hair-treating substance which is sandwiched between the walls of the cover piece will retain its position securely in the crevices or recesses in the material and thus remain evenly distributed over the entire surface of the same, which is an important 45 advantage in the use of this class of article.

In Fig. 6 I show a slightly modified form of the structure in which the turned over edges 15, of the cover piece are dispensed with, and in this construction the powdery contents will remain in place and particularly after the fabric and the powder have been wetted.

From the foregoing description it will 50 be readily understood that in the use of

my improvements in the process of permanent waving of the hair, the member or appliance may be made in quantities in advance and stacked up in wet condition and, if preferred, may be placed in a container 70 as described, from which they are withdrawn one at a time as used. The container provides convenient means for supplying the wet devices in practically unlimited quantities so that the waving process 75 may be performed with assurance of having at hand the necessary number of the appliances for the work at hand. As the container is depleted, a fresh lot of the absorbent devices is placed therein in 80 moistened condition. In order to ascertain at a glance the quantity of the members stacked in the container, the front of the same may be made of glass of transparent character, or a transparent window may be 85 made in one of the walls of the container, which is kept air-tight.

In order to bring the absorbent material in direct contact at the meeting edges the same are left free from any part or substance, so that when the material is soaked with water the clean contacting surfaces will adhere more closely together and form a secure closure against escape of any of the hair-treating substance at this point. 90 This prepared member is in clean and wet condition when it is to be used and no mess is made by the operator at the time he is engaged in the operation and this makes his work neater and quicker than otherwise. In the use of the appliance made substantially of the dimensions herein shown, the article is folded longitudinally on its length and wrapped around the strand of twisted hair to be treated, and it 95 may then be secured thereto in any of the usual ways before placing over it the usual enclosing tube for the steaming or vaporizing action when the assembled parts are enclosed in an ordinary electric-heater. Of course the shape of the absorbent member 100 may be varied and it may be made in a long narrow strip from which the desired length may be cut at the time it is to be used and of the size required and the cut 105 section may be wound in helical form around the twisted strand of hair in applying the absorbent member.

I wish to be understood as not limiting my invention to the particular constructions 110 of the various different parts thereof, as many modifications may be made in the same, without, however, departing from the spirit of my invention.

Having thus described my invention, 115 what I claim and desire to secure by Letters Patent, is:

1. A hair waving device comprising material having a surface capable of receiving and retaining a hair-treating substance 120

distributed thereover and juxtaposed absorbent material constructed and arranged to be interposed between said retaining means and the treated hair.

5. 2. A hair waving device comprising recessed or pitted material capable of receiving and retaining in its superficial cavities a hair-treating substance and juxtaposed absorbent material constructed and arranged 10 to be interposed between said retaining means and the treated hair.

3. A hair waving device comprising material having a surface capable of receiving and retaining a hair-treating substance 15 distributed thereover and absorbent material placed on the said substance retaining material and covering the opposite sides thereof.

4. A hair waving device comprising recessed or pitted material capable of receiving and retaining a hair-treating substance and a sheet of absorbent material placed about said material and housing the same.

5. In a device for waving hair, a member 25 formed of plies of absorbent material, a hair-treating substance interposed between the plies and means intermediate between the plies for maintaining substantially uniform disposition of said hair-treating substance.

30 6. In a device for waving hair, a member for use in treating the hair having recesses therein for holding hair-treating sub-

stance and preventing its lateral displacement, and means for closing said recesses 35 and retaining said substance in place.

7. In a device for waving hair, a member having recesses therein for holding hair-treating substance and preventing its lateral displacement, a sheet of juxtaposed absorbent material having its marginal edges folded around the edges of said member. 40

8. Apparatus for use in waving natural hair on the head, the same comprising a moistening storage container provided with an automatically operating closure for sealing said container against the admission of air to maintain the moisture content thereof, and a group of absorbent hair-treating 45 appliances arranged within said container and maintained moist therein, said moist appliances being capable of being withdrawn one at a time through said closure for use as needed.

9. A container for receiving and holding 55 a stack of moistened pad-like hair waving appliances and provided at or near its bottom with an opening for withdrawing the lowermost one of the stack, and an automatically closing door for closing said opening in the container.

Signed at New York city, in the county of New York and State of New York, this 21st day of September, A. D. 1921.

CHARLES NESSLER.
